CARTON

Robert Van Rosen, New York, N. Y., assignor to
 J. Makowsky Corporation, a corporation of New
 York

Application March 26, 1947, Serial No. 737,248

5 Claims. (Cl. 229—22)

1

The invention relates to a carton or box which may be made from a single sheet of material. The material may be of any suitable character such for instance as cardboard, plastic or the like. The sheet material may be cut into a suitably shaped blank which may be scored for folding lines and provided with suitable engaging or locking elements for holding the device in folded or closed condition.

The invention is particularly directed to a carton which will be triangular in cross section and may be used as a closed container or a display device. There may be provided in one or more walls of the device an opening or window which may be opened or closed with a transparent insert or cover. One wall of the device may be extended beyond the apex of the triangle to form a handle or an enlarged display background for the contents of the carton. When desired there may be an opening or aperture in the extended wall and this may form a continuation or supplement to the opening in the main wall.

Without limiting the invention thereto, but to more clearly explain it, several embodiments thereof are illustrated in the accompanying drawings in which Figure 1 is a plan view of one form of blank which may be folded into a display carton. Figs. 2 and 3 are perspective views of the blank of Fig. 1 partially folded. Fig. 4 is a side elevation of a completed carton showing a device displayed therein. Fig. 5 is a side elevation of a completed carton showing the extended wall centrally disposed. Figs. 6 and 7 are perspective views of forms of carton particularly adapted to specific forms of devices contained or displayed therein. Fig. 8 is a plan view of an optional form of blank and Fig. 9 is a perspective view of a carton made from the blank of Fig. 8.

The specific sizes, shapes, contours, arrangements and forms shown of all the elements of the device are not essential to the invention. The specific embodiment shown is triangular in shape and there may be an extension from its top but it may be turned and used in any other position. Without limiting the use or construction of the device or the position of the various members, but for convenience of description, arbitrary terms of location will be employed. One wall will be referred to as front and one as back or rear, irrespective of where it may be positioned, and likewise walls and members will be referred to as right and left as they appear on the drawings. The various sections of the blank which make up the carton are of various shapes and

2

sizes, some being longer in one direction and some in another, but for clearness the terms length, top and bottom may be used with respect to the extent from top to bottom, as shown in Fig. 1, while width or sides may be used with respect to extent from side to side as shown in Fig. 1.

As shown in Fig. 1, the blank may consist of a front member 10 which may be provided with a more or less centrally disposed opening or aperture 11. Dotted lines are employed to indicate lines of folding which may be scored on the blank. There is articulated to the top of the front member 10 a member 12 which may be provided with a slot 13 open at its margin and corresponding in contour with the upper portion of the opening 11. The member 12 may be folded down to overlie the upper part of member 10 with its slot 13 in register with the opening 11 and thus reinforce this part of the device which is to form the handle of the carton or the display background for a device contained in it. It will be noted that the ends of the member 12 are cut away slightly at their outer edges at 14 and 15. When the member 12 is folded against the member 10, the cut out 14 will lie adjacent the upper part of a right side wall member 16 and the cut out 15 will lie adjacent the upper part of a left side wall member 17. The side wall members 16 and 17 are each triangular in shape and of substantially the same size and are articulated respectively at the right and left sides of the front wall member 10 so that they may be folded forwardly at right angles to the member 10. The cut outs at 14 and 15 allow this folding without pinching, wrinkling or deforming the member 12. At the other side of the right wall member 16 is articulated a rear wall member 18 which may correspond substantially in shape and dimensions with the lower portion of the member 10. In the upper margin of 18 may be provided a slot 19 corresponding substantially in shape and size with the lower portion of the opening 11. The rear member may be folded to the left in Fig. 1 so as to bring its upper edge against the lower ends of the member 12 so as to hold it in place against the upper part of the member 10. Thus, the member 12 is articulated to the top of the front wall member and is turned downwardly under the rear wall member 18. At the same time this folding will bring the slot 19 in register with the lower part of the aperture 11 as indicated in Fig. 4. At its other side, a tab 20 may be articulated to the rear wall 18. The tab 20 may be folded back at a right

angle toward the front member 10. The left side wall member 17 may be folded up at a right angle to the front member 10 so as to lie against the tab 20 which may thus form a reinforcement for it. The tab 20 is shown as substantially the same size and shape as the member 17 to better form a reinforcement. This size and shape of the tab 20 is not essential and may be varied. A chief purpose of the tab 20 is to form a seat for a slit 21 made in or adjacent the fold line between 18 and 20 and arranged to receive a tongue 22 articulated to the rear side of the member 17. The tongue 22 is provided with grooves 23 at one or both sides of its root so as to lock it into the slit 21 and hold the device together in the folded position.

Articulated to the bottom edges respectively of side walls 16 and 17 are members 24 and 25 which may be folded in a right angle to form inner bottom walls for the carton. To the bottom edge of the front wall member 10 is articulated a member 26 which may be turned rearwardly to lie against the members 25 and 24 and form an outer bottom wall for the carton. Articulated to the end of the member 26 is a tab 27 which may be turned up and inserted between the lower edge of the rear wall 18 and sides of the inner bottom wall members 24 and 25 to lock the bottom in place and hold it closed.

The completed carton is shown in Fig. 4 where a device X is illustrated in display position. X may represent any desired device, a lipstick being indicated as resting in the carton and extending through the aperture 11 with its upper end lying against the upper part of the front member 10 so as to make an attractive arrangement against the inclined front member 10.

If it is desired, the upper part of the front member 10 may be slightly bent or turned on the line or scoring 28, 28 (which scoring may be omitted when the carton is to be used as shown in Fig. 4) at about the top of the side walls 17 and 18. Thus, instead of being inclined in line with the lower part of the front wall 10 its upper part may be vertical, as shown in Fig. 5, fitting more or less snugly over the top of the lipstick or the like, and so holding it securely in place in the carton. The reinforcing member 12 will move with the upper part of 10 when it is bent vertically and the cut out portions 14 and 15 may allow the member to move without binding or disturbing other parts of the carton.

The specific shape of the article to be contained in the carton is not important to the invention which may be adapted to various devices by suitable changes in sizes, proportions, shapes, etc. In Fig. 6 is indicated a carton containing a device having a characteristically shaped head or stopper, such as a perfume bottle, for example, in which the upper part of aperture 11 and slot 13 have been correspondingly shaped to secure and hold the device. The aperture 11 and the slots 13 and 19 may be suitably formed to receive a device Z having angular contour, as indicated in Fig. 7.

In Fig. 8 is shown a blank in which the front wall member 10a is no longer than the side wall members 16 and 17 and in which the member 12a articulated to the top of the front wall member 10a is relatively small and may be turned downwardly and under the rear wall member and may lie against the inner side of the rear wall member 18 closing the triangularly shaped carton at its apex, see Fig. 9. In this construction the aperture 11 and slots 13 and 19 may be omitted

and all the walls be plain or unbroken. There may be provided means for seeing the contents, however, such as an opening 30 in one wall, here shown as centrally disposed in the front wall. This inspection opening may, if desired, be closed by any suitable material which may be transparent.

I claim as my invention:

1. In a carton formed from a single sheet of material, a front wall member having an aperture therein, a reinforcing member articulated to the top of the front wall and overlying part of the front wall member and having a marginal slot in register with part of the aperture, a triangular right side wall member articulated at one side to the right side of the front member and turned at a right angle therewith, a rear wall member articulated to the other side of the triangular member and turned at a right angle therewith and engaging at its upper end with the reinforcing member and having a marginal slot in register with part of the aperture, a reinforcing triangular wall member articulated to the other side of the rear member turned at a right angle therewith, a triangular left side wall member articulated to the left side of the front member and turned into contact with the reinforcing triangular member, a slit at the joint between the rear member and the triangular reinforcing member, a grooved tongue on the left side member locking in the slit, inner bottom members articulated to the bottoms of the right and left wall members, a bottom member articulated to the bottom of the front member and in contact with the inner bottom members, and a locking tab articulated to the rear edge of the bottom member and engaging between the rear wall and the inner bottom members.

2. In a carton formed from a single sheet of material, a front wall member, a reinforcing member articulated to the top of the front wall and overlying part of the front wall member, a triangular right side wall member articulated to the right side of the front member and turned at a right angle therewith, a rear wall member articulated to the other side of the triangular member and turned at a right angle therewith and engaging at its upper end with the reinforcing member, a reinforcing triangular wall member articulated to the other side of the rear member turned at a right angle therewith, a triangular left side wall member articulated to the left side of the front member and turned into contact with the reinforcing triangular member, a slit at the joint between the rear member and the triangular reinforcing member, a grooved tongue on the left side member locking in the slit, inner bottom members articulated to the bottoms of the right and left wall members, a bottom member articulated to the bottom of the front member and in contact with the inner bottom members, and a locking tab articulated in the rear edge of the bottom member and engaging between the rear wall and the inner bottom members.

3. In a carton formed from a single sheet of material, a front wall member having an aperture therein, a reinforcing member articulated to the top of the front wall and overlying part of the front wall member and having a marginal slot in register with part of the aperture, a triangular right side wall member articulated to the right side of the front member and turned at a right angle therewith, a rear wall member articulated to the other side of the triangular member and turned at a right angle therewith and

engaging at its upper end with the reinforcing member and having a marginal slot in register with the aperture, a reinforcing triangular wall member articulated to the other side of the rear member turned at a right angle therewith, a triangular left side wall member articulated to the left side of the front member and turned into contact with the reinforcing triangular member, a slit at the joint between the rear member and the triangular reinforcing member, a grooved tongue on the left side member locking in the slit, inner bottom members articulated to the bottoms of the right and left wall members, a bottom member articulated to the bottom of the front member and in contact with the inner bottom members, a locking tab articulated to the rear edge of the bottom member and engaging between the rear wall and the inner bottom members, and scoring on the front wall member at the top of the rear wall member so that the upper part of the front wall member and its reinforcing member may be turned at a right angle to the bottom member.

4. In a carton formed from a single sheet of material, a front wall member, a reinforcing member articulated to the top of the front wall and overlying part of the front wall member, a triangular right side wall member articulated to the right side of the front member and turned at a right angle therewith, a rear wall member articulated to the other side of the triangular member and turned at a right angle therewith, a triangular left side wall member articulated to the left side of the front member and turned at a right angle therewith, a grooved tongue on the left side member locking with the rear wall member, inner bottom members articulated to the bottoms of the right and left wall members, a bottom member articulated to the bottom of the front member and in contact with the inner bottom members, and a locking tab articulated to the rear edge of the bottom member and engaging between the rear wall and the inner bottom members.

5. In a carton formed from a single sheet of

material, a front wall member, a reinforcing member articulated to the top of the front wall and overlying part of the front wall member, a triangular right side wall member articulated to the right side of the front member and turned at a right angle therewith, a rear wall member articulated to the other side of the triangular member and turned at a right angle therewith and engaging at its upper end with the reinforcing member, a tab articulated to the other side of the rear member turned at a right angle therewith, a triangular left side wall member articulated to the left side of the front member and turned into contact with the tab, a slit at the joint between the rear member and the tab, a tongue on the left side member locking in the slit, inner bottom members articulated to the bottoms of the right and left wall members, a bottom member articulated to the bottom of the front member and in contact with the inner bottom members, and a locking tab articulated to the rear edge of the bottom member and engaging between the rear wall and the inner bottom members.
